(57) **CLAIM**

The ornamental design for a controller with sensor for air cleaner, as shown and described.

DESCRIPTION

FIG. 1 is a front, top and right side perspective view of a controller with sensor for air cleaner showing our new design;

FIG. 2 is a rear, bottom and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a front, top and right side perspective view showing a condition in which a tray for verification of dust is withdrawn thereof;

FIG. 10 is a rear, bottom and left side perspective view showing a condition in which the tray for verification of dust is withdrawn thereof;

FIG. 11 is a front elevational view showing a condition in which the tray for verification of dust is withdrawn thereof;

FIG. 12 is a top plan view showing a condition in which the tray for verification of dust is withdrawn thereof;

FIG. 13 is a bottom plan view showing a condition in which the tray for verification of dust is withdrawn thereof;

FIG. 14 is a right side elevational view showing a condition in which the tray for verification of dust is withdrawn thereof; and,

FIG. 15 is a left side elevational view showing a condition in which the tray for verification of dust is withdrawn thereof.
